UNITED STATES PATENT OFFICE

HARRY L. PURCHAS, OF McGRAW, NEW YORK

DESIGN FOR A BOX AND THE LIKE

Application filed June 23, 1931. Serial No. 40,302. Term of patent 7 years.

To all whom it may concern:

Be it known that I, HARRY L. PURCHAS, a citizen of the United States, and a resident of McGraw, in the county of Cortland and State of New York, have invented the new, original, and ornamental Design for a Box and the like, of which the following is a specification.

Reference is had to the accompanying drawings, in which

Figure 1 is a perspective view of my improved design for box and the like; and

I claim:
The ornamental design for a box and the like, as shown.

HARRY L. PURCHAS.
